(57) **CLAIM**

The ornamental design for a wall lamp, as shown and described.

DESCRIPTION

FIG. 1 is a first perspective view of a wall lamp showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the wall lamp thereof; and,

FIG. 10 is an enlarged view of the selected portion 10 in FIG. 2.

The broken lines shown in the drawings depict portions of the wall lamp that form no part of the claimed design.

1 Claim, 10 Drawing Sheets
